UNITED STATES PATENT OFFICE.

FERDINAND STRNAD, OF SCHMARGENDORF, NEAR BERLIN, GERMANY.

VALVE.

SPECIFICATION forming part of Letters Patent No. 727,484, dated May 5, 1903.

Application filed June 1, 1901. Serial No. 62,756. (No model.)

To all whom it may concern:

Be it known that I, FERDINAND STRNAD, engineer, of 14 and 15 Warnemünderstrasse, Schmargendorf, near Berlin, in the German Empire, have invented an Improvement in Valves with Discharged Tubular Slides; and I do hereby declare the nature of this invention and in what manner the same is to be performed to be particularly described and ascertained in and by the following statement, reference being had to the accompanying drawings and to the letters marked thereon.

This invention relates to improvements in valves; and its object is to provide an efficient device of this character adapted to prevent shock on opening and closing the same, which, as is well known, when a machine having the same runs at high speed produces a retarded opening of the ports.

To avoid these defects, the present invention consists substantially in rigidly connecting the valve with a tubular slide, which latter does not give free passage through the ports of the valve-casing until the valve is raised from its seat and has obtained a certain velocity, so that the raising takes place before the full pressure is exerted upon the valve—that is, with relief of pressure—and the raising, moreover, may be effected as slow as desired, while the opening of the ports in the valve-casing takes place with accelerated velocity. On the return motion of the valve similar operations occur in reverse order.

In the annexed drawings the improvements are shown applied to different constructions of valves in vertical sections, in which—

Figure 1 is an inlet-valve of a motor, such as a steam-engine. Fig. 2 is a corresponding outlet-valve. Fig. 3 is a suction-valve for pumps. Fig. 4 is a pressure-valve for pumps. Fig. 5 shows a section through a blower or compressor-cylinder. Fig. 6 shows a valve in which the projecting rings which constitute the valve-seatings are taken away by turning. Figs. 7 and 8 are so-called "maneuvering valves." Fig. 9 is a side view of the valve-casing and ports.

The valve is indicated by *a* and is rigidly connected with the tubular slide *b*, which covers the delivery-ports *c* in the valve-casing *k* and opens them in the before-mentioned

manner after the initial lifting of the valve. On the return stroke of the valve the tubular slide *b* closes the delivery-ports *c* suddenly, while the valve *a* still continues its motion with considerable velocity. The latter may be softly brought to its seat by means well known. The tubular slide *b* is, as represented in Fig. 1, preferably somewhat larger in diameter than the double-seated valve *a*, so that it is not necessary to increase the lift of the valve on account of the covering of the parts by the tubular slide.

Between the valve *a* and the tubular slide *b* is an intermediate chamber *d*, in which a pressure is set up which is intermediate the pressure above and below the valve and diminishes the loss of permeability to an important degree.

The compound tubular slide-valve can be applied to steam-engines, gas-engines, &c., in conjunction with rigid or adjustable distribution-regulators of well-known forms. For the inlet-valves of steam-engines which work with superheated steam the valve is worn off very little, since it only occasionally comes into contact with the superheated steam, and a lower pressure, as well as a lower temperature, prevails in the chamber *d*.

The valves, as in Figs. 3 and 4, which are designed for gases or liquids, compressors, vacuum-pumps, blowing-engines, may be geared or arranged automatically. In a pump-valve the opening when automatic takes place suddenly, so that in this case only the slowness of the seating has to be considered, while in geared pumps or blowing-engine valves also the lifting ought to be effected as softly as possible. In all cases an increased tightness is obtained in consequence of the several valve-seatings and of the intermediate chamber *d*.

In self-acting pump and blowing-engine valves the pressure in the space *d* will considerably accelerate the opening of the valve, which is particularly important for suction-valves of blowing-engines, as the resistance to suction is avoided, which often offers an inducement to use controlled slide-valves instead of the self-acting inlet-valves.

The pressure in the intermediate chamber can when desired be increased by leaving

small borings *f* in the valve, tubular slide, or valve-casing, which may be provided with regulating-screws *g* to allow a little pressure to enter from the cylinder to the chamber *d* of the suction-valve or from the pressure-space to the chamber *d* of the pressure-valve.

The efficiency of the valve is independent of the number of seats. These can be more or less than two.

10. The seats of the valves may be turned (see Fig. 6)—as, for instance, in the case when disengaging the gearing, the motion of the valve is to be arrested by means of air-cushions, or when the valves are to be actuated as the 15 slides and so move beyond the position in which they close the ports.

In the modification shown in Fig. 7 of a so-called "maneuvering-valve" a small relief-valve *v* is arranged to facilitate the lifting of

20. the main valve. This relief-valve is by means of a channel *i* in communication with the pressure-space covered by the valve *d*.

Having described the invention, what I claim is—

1. A valve having a rigid tubular perforated 25 extension of greater dimension than, and slideable with, the valve, and a casing therefor, the casing having delivery-ports adapted to register with the perforations in said extension.

2. A valve having a rigid slideable tubular perforated extension, the valve having an annular external chamber, and the extension being slideable with the valve, and a casing therefor, the casing having delivery-ports 35 adapted to register with the delivery-ports of said extension.

In witness whereof I have hereunto set my hand in presence of two witnesses.

FERDINAND STRNAD.
